(57) **CLAIM**

The ornamental design for a water bottle cover, as shown and described.

DESCRIPTION

FIG. 1 is a top perspective view of a water bottle cover showing my new design;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a top perspective exploded view thereof; and,

FIG. 10 is a bottom perspective exploded view thereof.

The broken lines showing the logo cut-out, the LED lamp, and construction seam in FIGS. 1–6, and FIGS. 8–10 are included for the purpose of showing environmental structure and form no part of the claimed design.
